UNITED STATES PATENT OFFICE.

HARRY B. MORGAN, OF ST. LOUIS, MISSOURI, ASSIGNOR TO GROOVER ENGINE COMPANY, OF ST. LOUIS, MISSOURI, A CORPORATION OF MISSOURI.

TRUNK OR BOX.

1,193,710.

Specification of Letters Patent. Patented Aug. 8, 1916.

Application filed July 19, 1915. Serial No. 40,609.

To all whom it may concern:

Be it known that I, HARRY B. MORGAN, a citizen of the United States, residing at St. Louis, Missouri, have invented a certain new and useful Improvement in Trunks or Boxes, of which the following is a full, clear, and exact description, such as will enable others skilled in the art to which it appertains to make and use the same, reference being had 10 to the accompanying drawings, forming part of this specification.

My invention relates generally to trunks, boxes, caskets or like containers, and more particularly to the formation of the joint 15 between the lid or cover and the body of the trunk or other container, the principal object of my invention being to equip the meeting edges of the cover and body of the container or the meeting edges of the two 20 parts of a container, with strips of metal which, in addition to forming a protection for the meeting edges, provide a joint which, when closed, is dust, water and moth proof.

25 My improved joint, while particularly designed for use on trunks, is applicable for all forms of packing and storage boxes, for caskets, chests and all similar containers, wherever it is desired to exclude dust, moisture, moths and the like.

With the foregoing and other objects in view, my invention consists in certain novel features of construction and arrangement of parts, hereinafter more fully described, 35 claimed and illustrated in the accompanying drawings, in which—

Figure 1 is a sectional view through portions of a trunk or box, and showing the meeting edges thereof equipped with strips 40 as contemplated by my invention, said meeting edges being slightly separated. Fig. 2 is a sectional view similar to Fig. 1 and showing a closed joint between the meeting edges of portions of a trunk or like container. Figs. 3 and 4 are perspective views of the metal strips utilized in forming the joint contemplated by my invention.

Referring by numerals to the accompanying drawings, 10 and 11 designate the walls 50 of a trunk, box or the like, and secured to wall 10 is a strip 12, a portion 13 of which projects a substantial distance beyond the edge of wall 10 which meets the edge of wall 11, and the inner face of this project-

ing portion 13 is slightly beveled as designed by 14.

The metal strip which forms one of my improved joint members and which is applied to wall 10 and strip 13 is preferably formed of resilient phosphor-bronze and 60 comprising a base portion 15 which is secured in any suitable manner to the edge of wall 10 and extending outwardly over the beveled face 14 is an intermediate section 16, the same being curved or bowed outwardly so that its central portion is normally spaced apart from the beveled face 14. The outer portion 17 of this strip member extends outwardly substantially at right angles to intermediate portion 16 and said 70 outer member overlies and is secured in any suitable manner to the edge of strip member 13. The outer edges of portions 15 and 17 are rebent as designated by 15^a and 17^a to form beads or finished edges. It will be 75 noted that the strip or joint member just described when completed is substantially Z-shape in cross section.

Secured to wall 11 in any suitable manner 80 is a strip 18, the same being set backward from the edge of said wall a sufficient distance to accommodate the projecting portion 13 of strip 12 when the joint is closed. Thus, a portion 11^a of wall 11 projects 85 beyond said strip 18 and this projecting portion receives a metal strip which cooperates with the metal strip previously described in forming a tight joint when the parts to which said strip are applied are in closed position. This second strip is preferably 90

constructed of resilient phosphor-bronze and comprises an inner section 19 which overlies and is secured to the inner face of portion 11^a near the edge thereof. Extending at right angles to this section 19 is a section 95 20 which overlies the edge of projecting portion 11^a and extending from this intermediate section 20 is a section 21 which is bent slightly outward to form a resilient tongue, the same overlying the outer face of portion 100 11^a. The intermediate section 20 is secured in any suitable manner to the edge of projecting portion 11^a. The edges of this strip member are rebent to form beads or finished edges, the same being designated by 105 19^a and 21^a. This second strip or joint member when finished is substantially U-shape in cross section with one of its legs slightly

longer and bent outwardly relative to the other.

If desired, a finishing strip 22 of either metal or wood may be secured to the face 5 of wall member 10 on the side opposite the side to which strip 12 is secured, a portion of said finishing strip projecting beyond the edge of wall 10 and when the joint is closed, the projecting portion 11^a of wall 11 occupies 10 the pocket between the projecting portion of said strip 22 and the curved intermediate portion 16 of the strip which is applied to wall 10.

The strips contemplated by my invention 15 serve as a protection for the meeting edges of the container to which they are applied, and said strips present a neat and finished appearance. When the parts of the trunk or box to which the strips are applied are 20 open or separated, the curved central portion 16 is bowed outwardly away from the inclined or beveled face 14, and the resilient member 21 occupies an angular position away from the face of portion 11^a of wall 11, 25 as seen in Fig. 1.

When the parts of the trunk or other container are closed, the sections 15 and 20 of the two strips lie in direct contact with each other and likewise, portions 16 and 21 are in 30 direct contact with each other and by virtue of the resiliency in the metal of which the strips are formed, portion 16 will be forced toward the beveled face 14 and the free edge of resilient portion 21 will be 35 forced toward wall 11 as shown in Fig. 2.

The joint contemplated by my improved construction, when closed, is effective in preventing the passage of dust, water, moths, and the like, and consequently said joint is 40 particularly desirable for use between the meeting edges of trunks, boxes, chests, caskets, and like containers.

The strip can be easily and cheaply manufactured, and can be readily applied for use.

It will be readily understood that minor 45 changes in the size, form and construction of the various parts of my improved joint can be made and substituted for those herein shown and described, without departing from the spirit of my invention, the scope of 50 which is set forth in the appended claims.

I claim:

1. The combination with a pair of walls, the edges of which are adapted to meet, of a strip of metal applied to one of the meeting edges, said strip being of substantial Z-shape in cross section, the central portion of said strip being resilient and curved outwardly with respect to the face of the part to which it is applied, and a metal strip applied to the other edge, which last mentioned strip is substantially U-shape in cross section with one of its legs yielding with respect to the part to which said strip is applied. 60

2. The combination with a container having a pair of walls, the edges of which are adapted to meet and said meeting edges being provided with corresponding shoulders, of a metal strip applied to one of the 70 shouldered edges, said strip being substantially Z-shape in cross section, and a metal strip applied to the projecting portion of the other shouldered edge, which last mentioned strip is substantially U-shape in cross 75 section and one of the legs of said strip being free at one end so as to yieldingly engage a portion of the strip on the other shouldered edge when the two edges are brought together. 80

In testimony whereof I hereunto affix my signature in the presence of two witnesses, this 15th day of July, 1915.

HARRY B. MORGAN.

Witnesses:

M. P. SMITH,
M. A. HANDEL.
